US00D579010S

(12) **United States Design Patent**
Tseng

(10) **Patent No.:** **US D579,010 S**
(45) **Date of Patent:** **** Oct. 21, 2008**

(54) **WIRELESS MODEM**

(75) Inventor: **Yi-Hsuan Tseng**, Taipei (TW)

(73) Assignee: **Quanta Computer Inc.**, Tao Yuan Shien (TW)

(**) Term: **14 Years**

(21) Appl. No.: **29/281,142**

(22) Filed: **Jun. 15, 2007**

(51) **LOC (8) Cl.** **14-03**

(52) **U.S. Cl.** **D14/242; D14/358; D14/240**

(58) **Field of Classification Search** **D14/242, D14/496, 240, 167, 302, 314, 348-358, 363, D14/383, 433; D13/149, 184; D3/201, 273; 379/220.01, 221.09, 220.14, 25, 93.09, 93.19, 379/156, 900, 338-339, 441; 711/100, 115; 361/658, 725, 752; 369/272.1, 273, 75.11; 360/133, 79.01, 97.03**

(57) **CLAIM**

The ornamental design for a wireless modem, as shown and described.

DESCRIPTION

FIG. 1 is a front, side perspective view of a wireless modem showing my new design;

FIG. 2 is a left side elevational view thereof;

FIG. 3 is a right side elevational view thereof;

FIG. 4 is a rear elevational view thereof;

FIG. 5 is a front elevational view thereof;

FIG. 6 is a top plan view thereof;

FIG. 7 is a bottom plan view thereof; and,

FIG. 8 is a front, side perspective view of a wireless modem showing my new design with rotatable antennas mounted thereon in the open position.
